UNITED STATES PATENT OFFICE.

FRANCIS A. JOHNSON, OF POWHATAN, ARKANSAS.

CAR-COUPLING.

SPECIFICATION forming part of Letters Patent No. 447,154, dated February 24, 1891.

Application filed June 20, 1890. Serial No. 356,073. (No model.)

To all whom it may concern:

Be it known that I, FRANCIS A. JOHNSON, of Powhatan, in the county of Lawrence and State of Arkansas, have invented a new and Improved Car-Coupler, of which the following is a full, clear, and exact description.

The object of the invention is to provide a new and improved car-coupler which is simple and durable in construction, very effective in coupling, and adapted to couple cars of varying heights and without requiring the operator to step between the cars.

The invention consists in certain parts and details and combinations of the same, as will be described hereinafter, and then pointed out in the claims.

Reference is to be had to the accompanying drawings, forming a part of this specification, in which similar letters of reference indicate corresponding parts in all the figures.

Figure 1 is a perspective view of the improvement as applied. Fig. 2 is an enlarged side elevation of the same with parts of the car in section. Fig. 3 is a transverse section 25 of the same on the line 3 3 of Fig. 2, and Fig. 4 is a similar view of the same on the line 4 4 of Fig. 2.

The draw-head A, held on one end of the car B, is provided with the usual central opening C, in which is adapted to pass the arrow-head D' of the coupling-link D, as is plainly shown in Fig. 1. The arrow-head D' of the coupling-link is adapted to open and to engage transversely-extending plates E and E', fitted 30 to slide in suitable bearings formed in the draw-head A near its outer end.

The two plates E and E' are connected with each other at the top and bottom by springs F, passing through suitable openings C', arranged transversely in the draw-head above and below the central opening C. When the plates E and E' are in a closed position, as shown in Figs. 3 and 4, their inner edges nearly touch each other, so that the arrow-head D', when entering the opening C, passes 45 between the two plates E and E' and presses the same outward against the tension of the springs F, and when the arrow-head has passed in to the rear of the said plates the latter again close by the action of the springs F, so 50 that the coupling-link D is held in place in

the draw-head, the inner ends of the plates E and E' resting on the shank of the arrow-head.

In order to open the plates E and E', so as to permit the coupling-link D to be withdrawn, the following device is provided: On each of the plates E and E' are secured two or more friction-rollers G, arranged longitudinally and adapted to be engaged by inclines H, formed on two bars I and I', respectively connected with each other at their upper ends across the top of the draw-head A by a rod J. The bars I and I' are fitted to slide in a bearing formed on one side by the plates E or E', respectively, and at the other side by a strip K, secured to each side of the draw-head. (See Fig. 2.)

The connecting-rod J is pivotally connected with one end of a bell-crank lever L, fulcrumed at the end of the car and pivotally connected by its other arm with a crank-arm N, fastened on a transversely-extending shaft O, mounted to turn in suitable bearings on the end of the car B. Each outer end of the shaft O is provided with a handle P, which permits the operator to turn the said shaft O from either side of the car, so that the bell-crank lever L is caused to lift the rod J upward, so as to slide the bars I and I' vertically. This vertical movement of the bars I and I' causes the inclines H to engage the friction-rollers G, which are pressed outward and cause an outward sliding of the plates E and E'. The coupling-link D can then be withdrawn from the open plates E and E'. As soon as the operator releases the handle P the springs F return the plates E and E' to the normal closed position. The inclines H of the bars I and I' terminate in the straight vertical edges H', so that in case the vertical movement of the bars is continued the friction-rollers G travel onto the said straight edges H', whereby the plates E and E' are locked in an outermost position. To unlock, the shaft O is turned in an opposite direction to slide the bars I and I' downward. This is frequently necessary when it is not desired to couple cars and in case the latter are shifted about on the tracks.

In order to open the plates E and E' from the top of the car, the shaft O is provided with

the crank-arm Q, connected by a rod R with a bell-crank lever S, fulcrumed on the top of the car, and which when turned acts on the shaft O in the same manner as when the arms 5 P are manipulated, as previously described.

When the plates E and E' are in their normal position and it is desired to couple the cars, the coupling-link D, when moving with its head D' in the central opening C of the 10 draw-head A, presses the two plates E and E' apart, as previously described, so that the arrow-head is locked in place in the draw-head. The two cars are then coupled.

When it is desired to uncouple the cars, 15 the operator simply turns either of the handles P or the lever S on top of the car, so that the plates E and E' are opened and the link D is withdrawn on moving the two cars apart.

The opening C in the draw-head is made of 20 considerable height and the plates E and E' are similar, so as to fill the entire height of the said opening. Thus when two cars of different heights are coupled together the link D can readily pass into the opposite draw-head and engage the plates E and E', as above 25 described.

Having thus described my invention, what I claim as new, and desire to secure by Letters Patent, is—

30 1. The combination, with the draw-head and the transversely-sliding spring-pressed plates in the sides thereof, of parallel vertically-reciprocating bars having inclines to engage the said plates and throw them outward, substantially as set forth.

35 2. The combination, with the draw-head and the transversely-sliding spring-pressed plates in the sides thereof, of vertically-reciprocating

ing bars at the outer sides of the draw-head connected at their upper ends and provided 40 with inclines on their outer edges to throw the said plates apart, and a vertically-rocking lever connected with the upper ends of the said bars, substantially as set forth.

3. In a car-coupler, the combination, with a 45 draw-head, of plates arranged vertically and adapted to slide transversely in the draw-head to meet near the center of the central opening, and springs connecting the said plates with each other to hold the same in a closed 50 position, substantially as shown and described.

4. In a car-coupler, the combination, with a draw-head, of plates arranged vertically and adapted to slide transversely in the draw-head to meet near the center of the central opening, 55 springs connecting the said plates with each other to hold the same in a closed position, and means, substantially as described, for moving the said plates apart, as set forth.

5. In a car-coupler, the combination, with 60 the draw-head, of plates arranged vertically and adapted to slide transversely in the said draw-head and toward and from each other, springs connecting the said plates with each other, friction-rollers held on the outer ends 65 of the said plates, bars fitted to slide on the sides of the draw-head and provided with inclines adapted to engage the said friction-rollers, and means, substantially as described, for raising or lowering the said bars to open 70 the said plates, substantially as shown and described.

FRANCIS A. JOHNSON.
